S. B. HASELTINE,
YOKE AND DRAW BAR CONNECTION,
APPLICATION FILED APR. 27, 1918.

1,286,612.

Patented Dec. 3, 1918.

UNITED STATES PATENT OFFICE.

STACY B. HASELTINE, OF CHICAGO, ILLINOIS, ASSIGNOR TO WILLIAM H. MINER, OF CHAZY, NEW YORK.

YOKE AND DRAW-BAR CONNECTION.

1,286,612.

Specification of Letters Patent. Patented Dec. 3, 1918.

Application filed April 27, 1918. Serial No. 231,061.

To all whom it may concern:

Be it known that I, STACY B. HASELTINE, a citizen of the United States, residing at Chicago, in the county of Cook and State 8 of Illinois, have invented a certain new and useful Improvement in Yoke and Draw-Bar Connections, of which the following is a full, clear, concise, and exact description, reference being had to the accompanying 10 drawings, forming a part of this specification.

This invention relates to improvements in yoke and draw bar connections.

One object of the invention is to provide 15 a detachable draw bar and yoke connection wherein may be reemployed old yoke straps of the riveted type without modification, the arrangement being such that all the elements of the connection are held tightly in place 20 and all danger of looseness avoided.

The invention furthermore consists in the improvement in the parts and devices and in the novel combinations of the parts and devices herein shown, described and made the 25 subject of claims.

In the drawing forming a part of this specification, Figure 1 is a side elevation of a portion of a draw bar and yoke showing my improvements in connection therewith. Fig. 80 2 is a top plan view of the structure illustrated in Fig. 1. Fig. 3 is a vertical, sectional view, taken on the line 3—3 of Fig. 1. Fig. 4 is a detail perspective of the wedge block employed with the improvements. 85 And Fig. 5 is a view similar to Fig. 1, but illustrating a different embodiment of the invention.

Referring first to the construction shown in Figs. 1 to 4 inclusive, 10 denotes a stand- 40 ard draw bar provided with the usual rivet receiving holes 11 and 12 and upper and lower shoulders 13 and 14. The yoke designated by the reference A, is of the well known strap form bent to U-shape and hav- 45 ing the free arms thereof provided with the standardly located rivet holes 15 and 16 ar- ranged for alinement with the rivet holes 11 and 12 of the draw bar. The forward ends of the yoke arms are shown inturned, 50 as indicated at 17—17, to engage the draw bar shoulders 13 and 14.

In order to provide a detachable connection for the draw bar and yoke without modification of either, I employ the following arrangement: A pair of upper rela-

tively short pins 18—18 are inserted through the alined rivet holes 11 and 15. A corresponding pair of pins 19 are inserted upwardly into the rivet holes 12 and 16. All of said pins 18 and 19 are provided with 60 heads 20—20 which remain projecting beyond the adjacent surfaces of the yoke arms.

To hold the pins in proper position and prevent spreading of the yoke arms, I employ a band B having an upper horizontal 65 wall 21, side walls 22—22 and an inclined or beveled lower wall 23. The upper wall 21 is recessed on its under side, as indicated at 24 to accommodate the heads 20 of the upper set of pins 18, the recess 24, however, being 70 shallow enough so as to prevent the inner face of the wall 21 coming in direct contact with the upper arm of the yoke. Coöperable with the band B is a wedge block C. Said wedge block C is provided on its upper 75 face with a longitudinally extending groove 25 arranged to accommodate the heads 20 of the lower pins 19 as the wedge block C is shifted lengthwise of the yoke. The block C is inclined or beveled on its under face, as 80 indicated at 26, so as to coöperate with the inclined lower wall 23 of the band B. To force the wedge block tightly in position and to maintain it in position, I may employ a short bolt 27 and nut 28, said bolt 27 passing through suitable depending lugs 29 and 30 on the band B and block C, respectively. 85

With the arrangement above described, it is evident that the wedge block C coöperating with the band B, will positively hold the 90 headed pins in proper position and maintain the arms of the yoke tightly in engagement with the draw bar. In other words, looseness or rattling of any of the parts is positively eliminated and any variations in 95 manufacture or wear which may occur can be readily compensated for by adjusting the wedge block C.

In the construction illustrated in Fig. 5, the arrangement of draw bar, yoke and headed pins is the same as in the construction illustrated in the other figures. In the Fig. 5 construction, however, instead of recessing the under face of the upper wall of the band B', I employ a plate 31 which is 105 centrally recessed, as indicated at 32, to accommodate the heads of the pins, the ends of the plates 31 being upturned, as indicated at 33, to engage the edges of the band B'. 110

The band B' in this construction is made

of true rectangular formation with the lower wall 34 thereof extending horizontally and provided with an opening 35. In order to provide the inclined wall to coöperate with the wedge block C', I insert a detachable second wedge block 36 having an integral lug or projection 37 on its under face fitting within the opening 35. The block 36 is provided with an upstanding flange 128 through which the bolt 127 extends, said bolt 127 passing through the block C', as clearly described in Fig. 5. The band of the construction shown in Fig. 5 is somewhat cheaper to manufacture than that shown in Fig. 1 but the principle employed in both constructions is the same. It is evident that in both of the constructions as shown and described, the bands are prevented from longitudinal shifting by engagement with the upper headed pins, in the one instance the engagement being direct, and in the other instance indirect through the intermediary of an interposed plate.

I claim:

1. In a connection for draw bars and yokes having alined perforations adapted to receive fastening means, the combination with a plurality of elements adapted to be inserted within said perforations, of a rectangular single-piece band arranged to sur-

round the draw bar, yoke, and said elements when the same are assembled, said band being provided at one end with an integral inclined surface, and wedging means coöperable with said surface and interposed between said surface and an adjacent portion of the yoke.

2. The combination with a draw bar and yoke having alined perforations adapted to receive rivets or the like, of a plurality of headed pins extending within said alined perforations, the headed ends of the pins projecting beyond the adjacent portions of the yoke, a rectangular band surrounding the draw bar, yoke and pins, means coöperable with the headed ends of said pins arranged to prevent longitudinal shifting of the band, one wall of said band having an inclined surface and spaced from the adjacent arm of the yoke, a wedge coöperable with said inclined surface and interposed between the latter and the adjacent arm of the yoke, and means for drawing said wedge within the band to force all of the parts into tight engagement.

In witness that I claim the foregoing I have hereunto subscribed my name this 13th day of April, 1918.

STACY B. HASELTINE.
